ELECTROMAGNETIC LATCH TRIP SWITCH

Max L. Jeffrey, Shaker Heights, Ohio, assignor to
The National Acme Company, Cleveland, Ohio,
a corporation of Ohio

Application December 31, 1945, Serial No. 638,554

9 Claims. (Cl. 200—106)

1

This invention relates to improvements in switches, and more particularly to a quick acting multipole switch.

Although multipole switches have been contemplated heretofore, there have been certain disadvantages inherent in prior structures of which it is the purpose of the present invention to overcome. For instance, they have been relatively cumbersome in structure as well as expensive to manufacture. Furthermore, efforts to lighten the structure weakened it and made the operation thereof unreliable.

By the present invention, I have provided a switch which is extremely compact and yet contains a number of features only to be found in larger and more complicated devices. The switch of my invention is characterized by its ability to quickly make and break a circuit, thus eliminating the tendency of contacts, carrying heavy current, to arc. Furthermore, the contact carrying structures are such that although the contacts are relatively close together, the tendency to arc between contacts is reduced by increasing the path over which the arc would have to travel.

The invention also includes an improved snap action mechanism which provides a quick make and break of the contacts. There is also contemplated a new type of thermally operated control which causes the switch to automatically open upon a power failure or in the presence of a sustained overload.

Still other advantages of the invention and the invention itself will become more apparent from the following description of an embodiment thereof, which description is illustrated by the accompanying drawings, and forms a part of this specification.

In the drawings:

Fig. 1 is a side elevational view on a reduced scale of the switch of my invention;

Fig. 2 is an end elevational view on an enlarged scale thereof;

Fig. 45 is a side elevational view thereof;

Fig. 46 is an end elevational view of a movable contact member;

Fig. 47 is a side view thereof; and

Fig. 48 is a wiring diagram indicating one manner in which the apparatus may be used to control a circuit.

Briefly, the invention includes a housing having an operating shaft extending therethrough and which connects to a snap action mechanism. The snap action mechanism operates a movable contact carrying member which moves the movable contacts into engagement with sets of fixed contacts.

The snap action mechanism has means connected thereto to release it from the operating position to open the contacts in event of power failure. The same release means is also operable by a thermally controlled overload switch to open the contacts in event of an overload.

Referring now to the drawings, throughout which like parts have been designated by like reference characters.

The mechanism is provided with a housing which includes a base portion 10, the upper portion of which is closed by a cover 11 held on by screws 12 which extend through the cover and are threaded into bosses 13 on the base housing. The end of the base housing is provided with a protruding boss 14 through which an operating shaft 15 extends, the end of the shaft being serrated and carrying thereon the operating lever 16. The end of the lever is split, and a screw 17 permits the lever to be securely clamped to the shaft in any desired position.

The side of the housing is provided with a plurality of threaded bosses 18 adapted to receive conduits, not shown, and through which wires may be conducted into the interior of the mechanism to provide the desired electrical connections.

As can best be seen in Fig. 4, the shaft 15 extends into the interior of the housing, being journaled in a bushing 19, and having a flanged head 20, the flange 21 of which is seated on a packing member 22 disposed in a cup 23 on the end of the bushing 19. The outer end of the boss 14 is provided with a counterbore 24 surrounding the bushing, and a helical spring 25 is seated in the end of the counterbore with the other end bearing against a flange 26 on the shaft 15. The flange 26 is secured to the shaft by a pin 27 (Fig. 3) which extends through the flange and shaft. The spring urges the shaft and lever outward securely seating the flange 21 on the packing 22 in fluid and gas sealing relation. The head 20 is provided with a transverse slot 28 (Fig. 3) adapted for engagement with a tongue 29 of an operating member hereinafter described.

The snap operating mechanism is disposed in the housing adjacent the end with the operating handle or to the right as viewed in Fig. 4. Back of the snap mechanism the fixed contacts supporting blocks extend longitudinally of the housing on opposite sides, and the rotor which carries the movable contacts is disposed between the fixed blocks, being rotatably supported by its ends. A thermal overload mechanism is disposed in the lower portion of the housing on one side,

the rear side as viewed in Fig. 4 or the left as viewed in Fig. 6, and in the opposite side of the housing is a solenoid which operates in conjunction with the snap mechanism.

For a description of the snap operating mechanism reference will be had to Figs. 7 to 11, inclusive, wherein the mechanism is shown in detail, removed from its association with the other mechanisms.

10 As previously stated, the shaft 15 connects through the head 20 with the tongue 29. This tongue extends from the operating shaft 30 through the front of the snap mechanism support.

15 The snap mechanism is supported between a pair of vertical plates 31 and 32. The plate 31, the formation of which is best shown in Fig. 7, is provided with a pair of rearwardly bent ears 33 adapted to be secured to bosses 34 integral with and disposed on opposite sides on the bottom of the housing by screws 35.

20 The rear plate is connected in spaced relation to the front plate by spacers 36 and 36' which are riveted into the rear plate and secured to the front plate by screws 37 which extend through the front plate and are threaded into the spacers.

25 The right end of the shaft 30 is provided with an enlarged head 43 which carries the tongue 29. This head is rotatably journaled in an aperture in the plate 31 and is provided with a longitudinally extending slot 41 in which the end 42 of a spiral spring 43 is hooked, the spring encircling the shaft for approximately 3 convolutions and being hooked at 44 over the head of the screw 37 which is enlarged for that purpose. The spring is tensioned to urge the shaft 30 in a clockwise direction as viewed in Fig. 7.

30 The rear end of the shaft 30 is provided with a reduced extension 45 adapted to be journaled in the end of the rotor, the end of the rotor being journaled in the opening 46 in the plate 32, as will hereinafter more clearly appear, to provide a support for the end of the shaft 30.

35 The shaft 30 has secured therein at its mid portion by a pin 49 a lever 50 which depends downward midway between the plates 31 and 32. The lever is provided with inwardly extending recesses on opposite sides which form a neck 51, and the extremity is provided with portions 52 which extend laterally on opposite sides, the bottom faces of which are curved at 53 and 53' to provide cam surfaces.

40 Also carried by the shaft 30 is a second lever which is rotatably journaled on the shaft. The upper part of the lever has the same contour as the lever 50 and comprises two spaced parts 55 and 56 between which the lever 50 is disposed, as best shown in Fig. 9. The lower end of the lever is of generally square formation and supports a member 57 between the bottom ends which is riveted to the two parts and holds them in spaced parallel relation to each other. The lower surface of the member 57 is of generally arcuate formation and is provided with notch 58 extending transversely thereacross opposite the center of the lever. An opening extends through the notch toward the end of the lever 50 and a ball 60 is disposed therein.

45 The square portion 55 of the arm carries a housing 63 which is threaded into the arm and protrudes through an elongated aperture in the plate 31. This housing is provided with a bore in which is disposed a helical spring 64. The spring carries a head 65 engaging a ball 66 which is pressed into an opening 67 extending through

the end of the lever 50. This acts as a detent which tends to hold the two levers in predetermined relation to each other; they can, however, attain relative movement, in which event the ball is pushed out of the detent formed by the opening 61 and rides on the surface of the lever 50.

The lever 50 is adapted to drive the lever 55-56 through a C-shaped spring 70 of laminated construction. The spring surrounds the ends of the levers and arm with the free ends in engagement with the necked in portions 51 on opposite sides. It will, therefore, be seen that if the shaft 30 is rotated, the lever 50 is swung and that movement from the lever 50 is transmitted to the arm 55-56 through the spring 70. If the lever 55-56 meets with sufficient resistance, the ends of the spring are forced apart allowing the two levers to move relative to each other. If, however, the resistance against movement by the lever 55-56 is overcome, the spring 70 will cause this lever to swing quickly over into aligned relation with the other lever. This feature is utilized to cause the snap movement of the switch contacts. In carrying out this function, the arm 55-56 is held during the major part of swing of the lever 50, the C-shaped spring having its ends forced apart, the arm and lever moving out of relative alignment until at a predetermined position the arm is released, and the C-shaped spring snaps the arm into alignment with the lever. The arm being connected to the rotor carrying the movable contacts, a quick contact is made.

In carrying out this feature of the invention, the lever 55-56 is held against movement when the lever 50 is swung, by a catch, which catch is released by the cam surface on the lever after it has swung a predetermined amount. Supported between the plates 31 and 32 below the end of the lever 55-56 and to one side in the direction in which the lever is to swing is a block 72 which is provided with a square channel 73 extending through the block toward the axis of the lever. In the channel there is disposed a square plunger 74 which is provided with a bore 75 in which a spring 76 is seated. The end of the channel 73 is closed by a strip 77 which is held in place by screws 78. The spring 76 urges the plunger 74 upward into the notch 58, in which position it holds the lever 55-56 against movement. The ball 60 rests on the end of the plunger 74.

When the lever 50 is swung counterclockwise as viewed in Fig. 7, the lever 55-56 being held against movement by the plunger 74, the two necks on the two levers move out of alignment against the pressure of the C-shaped spring 70. Continued rotation of the lever 50 swings the end 52 between the square portions until eventually the cam surface 53 on the lever 50 engages with the ball 60, pressing the ball downward against the plunger 74. The plunger 74 is forced downward by the ball and is eventually forced out of the notch 58. This releases the lever 55-56, and the C-spring 70 snaps the lever 55-56 over into alignment with the lever 50.

After the two levers are swung to the right, as just described, the lever 55-56 is engaged by the second plunger 80 where it is locked, until the lever 50 is swung back, at which time the plunger 80 is released by the other end 53' of the lever 50 in exactly the same manner.

The faces 52' on the lever 52 are adapted to engage, upon overtravel of the lever, with the bushings or spacers 36' which serve as stops therefor. In the position shown, the snap mech-

anism is in an "off" position where the rotor and its contacts controlled thereby are open. When it is moved counterclockwise to the position just described, the tension on the spring 43 is increased. This spring normally tends to urge the lever back to the "open" position, but the tension is insufficient to overcome that of the C spring 70 and the ball and detent mechanism.

Means is provided, however, to release the plunger 80 in event of sustained overload, which allows the spring 43 to return both levers 50 and 55-56 back to their normal "open" and "off" positions.

As can best be seen in Fig. 11, the plunger 80 is provided with a longitudinally extending slot 81 in the lower end of which is disposed a pin 82. The pin extends transversely across the slot.

The rear end of the block 72 is formed with a vertically extending channel in alignment with the groove 81 and a lever 85 is pivotally supported in the channel 84 on a pin 87. This lever is provided with a projection 86 which, when the lever is rotated, engages the pin 82 and forces the plunger 80 downward. The upper end of the lever has a head 88 provided with a flat face 89 which is adapted to engage the bottom of the groove 81 and which serves as a stop to limit the inward movement of the lever, and hence the downward movement of the plunger. This lever is moved by the armature of a solenoid when a sustained overload occurs to cause the release previously described.

The solenoid is located in the lower right hand portion of the housing, as viewed in Fig. 6, and is shown in detail in Figs. 12 to 14, inclusive. It includes the E-shaped stator plates 91, and the winding 92 into which the stem 93 of the armature 94 is adapted to extend. A pair of mounting brackets are provided at the upper end and each comprises an inverted U-shaped member 96 secured through the laminations by rivets 97, out turned ears 98 being provided on the upper end.

The head of the armature is provided with a recess in which a pin 99 is secured by a rivet 100. The pin has a head 101 and a spring 102 which has one end bearing against the head and the other end against a plate 103 urges the armature to its outward or uppermost position as shown in the figures. The brackets 96 are secured to the plate 32 by screws 104, which extend through the brackets and are threaded into the plate. The other end of the solenoid is supported by a bracket 105, one end of which is secured to the strip 106 by bolts 107 that extend through the bracket and through the holes 108 in the end of the stator laminations.

In the operation of the solenoid, it is energized, by the circuit being controlled, to attract the armature into the winding against the pressure of the spring 102. In event of power failure, or as will hereinafter appear, in event of a sustained overload, the solenoid is de-energized and the spring 102 urges the armature outward. The head 101 engages the lever 88 which pulls the plunger 80 down out of the notch 58 releasing the lever 55-56 and the spring 43 rotates the mechanism to the "open" position.

As previously stated, the rotor which carries the movable contacts and the blocks which carry the fixed contacts are disposed to the rear of the snap operating mechanism and extend longitudinally of the housing. A supporting plate 110, similar in configuration to the plates 31 and 32, is provided and has rearwardly bent ears 111

adapted to rest on and be secured to bosses 112 at the bottom and end of the housing by screws 35. Extending between the rear plate 110 and the plate 32 which supports the back of the snap mechanism, on each side are strips 106. These strips hold the plates rigid and in properly spaced relation and provide means for supporting the fixed contact carrying blocks. They may be secured to the plates in any suitable manner, as by angle brackets 113, Fig. 3, or by providing in-turned flanges on the ends of the strips.

The fixed contact supporting members, as can best be seen from Fig. 6, are carried by the strips 106 on opposite sides of the housing, the one on the left side being disposed in a lower position than the one on the right and carrying contacts which face upward, while those on the right face downward.

The upper or right hand block is illustrated in Figs. 15 and 16, and the lower or left hand block in Figs. 17 and 18. The blocks are both formed of a suitable insulating material such as "Bakelite," the upper or right hand block 115 being of generally inverted L shape, being secured to the strip 106 by screws which extend through the strip and are threaded into the block. The strips are preferably seated in a longitudinally extending recess in the side of the block so that the outer face of the strip and the side of the block lie flush with each other. The upper and inner portion of the block is provided with fixed contacts, the faces 116 of which face downward and which are provided with stems 117 extending upward through the block and are secured by nuts 118 to a terminal strip 119. Each terminal strip is provided with a connecting screw 120 threaded through the strip and into a bushing 121 embedded in the block.

As can best be seen in Figs. 15 and 16, the material of the block extends upward between the strips and around the contact nut 118 to provide further insulation.

The lower or left hand block is illustrated in Figs. 17 and 18 and is shown in cross section in Fig. 6. It is likewise secured to one of the strips 106 and carries the fixed contacts, the faces 120 of which face upward. These contacts are carried in projections 121 which extend inwardly from the inner side of the block. Likewise, they are provided with stems which extend through the block and are provided with connecting nuts 122. Terminal strips 123 likewise connect the contacts to the terminal screws 124, which screws are threaded into bushings 125 that extend through the blocks, these being screwed on each end of the bushings whereby connection can conveniently be made to the top or bottom. It will also be noted that each of the blocks is provided with grooves between the contacts, those of the block 115 being indicated at 126, and those of the left hand block at 126'. It will be appreciated that the manner of connection of the contacts is a matter of choice and will be governed largely by the specific application of the switch. This increases the electrical resistance path between the contact, and as will later appear, allow the ribs 127 of the rotor to extend therebetween, thus safeguarding against flash over between the contacts.

The rotor, which carries the movable contacts, is rotatably supported intermediate the fixed contact blocks and adapted to be rotated to bring its contacts into engagement with the fixed contacts. The construction of the rotor can best be seen from Fig. 6, where it is shown in section,

and Figs. 19 to 22, inclusive, where it is shown removed from the assembly.

As best shown in Fig. 6, the rotor includes a body of insulating material, such as Bakelite, formed in two sections 130 which are secured together by a bolt 131 that extends through the sections. The heads 132 of the bolts are disposed in recesses in one of the sections and the securing nuts 133 secured in recesses in the other section. Each section is provided with a channel 134 extending across the abutting surfaces and which line up on the opposite sections to provide a passageway extending transversely through the rotor.

15 A movable contact carrying strip 135 is disposed in each of the passageways, being provided with a central aperture 136 through which the bolt 131 extends. The ends of each strip carry contacts 137 which face in opposite directions and toward the respective fixed contacts with which they will ultimately engage. On the opposite side from each of the contacts, helical springs 138 are provided, the ends of which are seated in recesses 139, and the other ends of 20 which engage the strip and tilt it in a counter-clockwise direction. The tilting of the strip is limited by inwardly extending bosses 140 on the members 138. Intermediate each contact strip 25 the rotor is provided with circumferentially extending ribs 127, which ribs are adapted to extend into, but out of contact with, the grooves or channels 126 and 126' on the blocks carrying the fixed contact to thus provide a circuitous resistance path which, as previously mentioned, 30 serves to prevent flash over between the contacts upon the breaking of a circuit.

The ends of the rotor are provided with trunnions 143 and 144 by which it is rotatably supported in openings in the plates 110 and 32. The trunnions are provided with stems 145 which are clamped in axial openings in the end of the rotor by bolts or studs 146. The trunnion 143 is provided with a projection 147 which extends transversely across the axis and is adapted to 40 be engaged in a slot 148 in the member 36 of the snap mechanism (see Fig. 9) the projection is also provided with an axial opening 149 adapted to receive the extension 45 of the operating shaft 38. The trunnion is thus supported in the opening 46 of the plate 32 and in turn provides a bearing support for the shaft 38. It will be noted that the movable contacts are so disposed that they may be rotated into contact with the fixed contacts on the opposite blocks, and when so moved, establish a circuit from the contacts 116 through the strips 115 to the other contacts 120.

As previously stated, thermally operated means is provided, which, in the presence of a sustained overload, causes the switch to be opened. Briefly, 45 this includes a resistance or heater element serially disposed in the circuit being controlled and which, upon a predetermined value of current therethrough, heats a thermostatic element which moves the contacts to the open position.

50 In the apparatus shown, there are two such devices, but since they are both the same, only one will be described. For a better understanding thereof, reference will be had to Figs. 23 to 28, inclusive. As best shown in Figs. 4 and 6, the fixed contact carrying block on the left side of the housing has secured on the under side a plate 152 which has suspended therefrom the thermostatic switches 153.

The switch is provided with a base plate 154 which is secured to the plate 152 by screws 155.

The plate is provided with pairs of legs 156 and 157 at opposite ends, each pair of which supports blocks 158 and 159 respectively. Each of the blocks is provided with axially aligned cylindrical bores 160 and 161 into which the ends of the thermostatic element 162 extend. The bores 160—161 are sufficiently large to provide ample clearance space for the thermostatic element, and to permit the desired expansion thereof as hereinafter described, and yet serve as a guide and protector therefor.

At this point, for a better understanding of the invention, reference is made to Figs. 29 to 33, inclusive, which illustrate in detail the thermostatic element. Generally, it comprises an insulated heater element which is disposed between a pair of nested cylindrical bi-metallic elements. The outer bi-metallic cylinder is split longitudinally and is provided with outwardly and longitudinally extending lips along the split edge engage with and operate the switch.

More specifically, as can be seen in Figs. 29 and 33, the outer bi-metallic element is bent into the form of a cylinder 163 which is split at 164, being provided with a pair of downwardly extending flanges 165. A pair of guide pins 166 are provided on the upper end of the element opposite to the flanges 165, being adapted for guiding engagement with notches 167 in the plate 156.

The heater element comprises a narrow strip of insulating material 168 which is preferably of mica, about which is wound the resistance wire 169. The ends of the wire are secured to metallic clips or bands 170 as by spot welding. Lead wires 171 are also connected to each of the clips 170. One end of the mica strip is provided with three apertures for the reception of hollow rivets 172 which hold the assembly together as later described.

The heater element is sandwiched between wide strips of mica 173, Fig. 31, of which there may be six, three being disposed on each side of the strip as shown in Fig. 32.

The mica strips 168 and 173 and the heater element 16 are all secured together by the rivets 172 which are inserted through the outer apertures 174, after which the assembly is rolled into cylindrical form and inserted through the outer bi-metallic element 163. A second bi-metallic element 163', Fig. 28, is inserted inside the rolled heater assembly, and a third rivet 175 is then inserted through the apertures 176 of the bi-metal element and through the center aperture of the heat assembly (174) to rivet the entire assembly together. When so assembled, the resistance, or heater element, is held in alignment with and between the bi-metallic elements, and the wide strips of mica 173 extend beyond the ends providing ample protection against short circuits. These ends are also the ends that extend into guiding relation with the bores 160—161 of the blocks 158—159. The bimetallic elements are designed to expand when heated to open up the cylinder moving the flanges 165 apart, which movement effects the operation of the switch.

The flanges 165 are engaged by means, which is adjustable, and which resists the outward movement thereof and thus determines the length of time for which an overload must exist before the switch is opened as well as to afford a snap action therefor. The flanges also engage a pair of levers which open the switch contacts.

As previously stated, the thermostatic element 163 is disposed with its ends in the bores of the

blocks 158 and 159 and with the pins 166 being guided by the notches 167 in the plate 156. The wires 171 of the heater element extend through notches 177 of the block 159 and are clamped therein by the clamp bar 178 which extends over the wires in the notches and is held in place by a screw 179 which is threaded into the block.

The means for controlling the time of operation of the switch and the operating levers, are supported on a block 180 which is secured to the lower ends of the blocks 158 and 159 by screws 181. This block (180) is best shown in Figs. 34 to 36, inclusive.

As can best be seen in Fig. 34, the block is formed with a channel 182 which extends transversely across the block and in which is disposed a pair of slides (Figs. 37-38 and Figs. 39-40). These slides are disposed in the channel, one on top of the other in nested relation. The slide, Figs. 39-40, includes a flat base portion 185 adapted to rest on the bottom of the channel, and one end of which is thickened at 186 to provide for lateral guiding engagement with the side of the channel. A pair of upwardly extending spaced tongues 187 are provided on the intermediate portion which provides a kerf therebetween, the tongues being adapted for engagement on opposite sides of one of the flanges 165 of the bi-metallic element. The remainder of the body 188 is relatively thin and adapted to have seated thereon the other slide element (Figs. 37-38) which comprises a body portion 190, at one end of which is provided a pair of upwardly extending tongues 191 disposed in spaced relation to each other and adapted to engage on opposite sides the other flange 165 of the bi-metallic elements. The slide 190 is adapted to seat on top of the thin portion 188 of the slide 185 in the channel 181, (see Figs. 35 and 36), and both slides are held in the channel by plates 193 that are secured to body 180 at the sides of the channel by screws 194.

When so secured in place, the tongues 187 and 191 extend above the channel at even height to each other and are in position to engage the spaced flanges 165 of the bi-metallic element.

Means is provided to hold the slides in position with the tongues 187—191 in properly spaced relation to each other and to restrict or resist the initial movement thereof by the bi-metallic element, in the form of a spring detent mechanism which engages notches in the sides of the slide. As best shown in Figs. 38 and 40, the slide 190 is provided with a notch 195 and the slides 185 with a notch 196. These two notches are so positioned that when the slides are in a predetermined position, one on top of the other, the notches are in vertical alignment with each other. The plate 180 is provided with a boss 197 which extends from the side of the channel 182 to the left, as viewed in Fig. 34, to the edge of the plate. This boss is provided with a bore or channel 198, the outer end of which is threaded, and a plunger 199 is disposed in the inner end of the bore, being provided with a rounded end 200. The plunger is adapted to be pressed inwardly through the channel 182 with the rounded end 200 in simultaneous engagement with the notches 196—195, by a spring 201. One end of the spring 201 engages with the plunger and the other end with a screw 202 disposed in the threaded end of the bore. The pressure of the spring on the plunger is determined by the screw 202 which may be locked in adjusted position by the nut 203.

It will therefore be seen that the slides must overcome the effect of the plunger to force it out of the notches 195—196 before they can move longitudinally in the channel 182, and that the pressure on the slides by a bi-metallic element, necessary to disengage them from the plunger, is dependent upon the adjustment of the screw 202. Therefore, when the bimetallic element is heated, the cylinder starts to open up. The opening movement is restrained until the pressure by the bi-metallic element upon the slides 190—185 is sufficient to force the plunger out of the notches 195—196. When this occurs, the resiliency of the bi-metallic elements snap the slides quickly to the limit of their movement in the outermost position. This thus provides a quick action for opening the contacts.

Inasmuch as the spring and detent mechanism restrain the movement of the slides, and the slides in turn restrain the movement of the bi-metallic element, the movements of the bi-metallic elements are delayed, depending upon the pressure extended by the plunger in the slide notches. The time of operation may, therefore, be predetermined.

The flanges 165 engage between the ends of a pair of levers, which levers open the contacts. The base 180 is provided with a pin 205, disposed at the end of the base at the center line thereof, and upon which are disposed a pair of levers (Figs. 41—43a, inclusive). Each of the levers comprises a body portion 206, which is apertured at 207, to fit over the pin 205. The levers are each provided with an offset arm 208 from the end of which rises a flange engaging portion or pin 209. The other end of each lever is provided with an upwardly extending pin 210 adapted for engagement with the contact carrying members. The two levers are adapted to be pivotally disposed on the pin 205, one on top of each other, as best shown in Figs. 23 and 28. The pins 209 and 210 of one lever are longer than those of the other lever so that when they are disposed in assembled position, they rise to the same height. The flanges 165 of the bi-metallic element extend between the pins 209. The other end of each lever is provided with an upwardly extending pin 210 adapted for engagement with the contact carrying members. The two levers are adapted to be pivotally disposed on the pin 205, one on top of each other, as best shown in Figs. 23 and 28. The pins 209 and 210 of one lever are longer than those of the other lever so that when they are disposed in assembled position, they rise to the same height. The flanges 165 of the bi-metallic element extend between the pins 209 and are adapted to move the ends outward upon expansion of the element, and since the two levers cross each other, the ends 210 are likewise moved outward, scissors fashion, to open the contacts.

The contacts are supported by the block 158, Fig. 28, which is provided with outwardly projecting portion 212 having three vertically extending slots. The center slot 213 receives therein the fixed contact assembly (Figs. 44 and 45) which comprises a pair of contact carrying strips 214 that are spot welded to a member 215 on opposite sides thereof and which extend downwardly and outwardly with the ends 216 in spaced parallel relation to each other and carrying the outwardly facing contacts 217. The member 215 is provided with serrations 218 along the edge thereof. The center slot is somewhat wider than the others, and the contact assembly is held

therein by a clamp bar 219 and screws 220 which extend through the clamp bar and are threaded into the portion 212 of the block 158. The clamp bar engages with the serrations and securely holds the assembly in place. The member 215 is also provided with a solder lug 222 which extends outward from the edge of the member and adapted to receive connecting wires, not shown.

The outer movable contact members, illustrated in Figs. 46 and 47, included the support member 225, which, like the member 215, has a serrated edge. A single contact carrying strip 226 is secured to the side of the member. This strip is provided with a double U-shaped bend to provide flexibility thereto, the contact 227 being carried on the laterally extending end. Two of these members are provided and are each supported in the end slots, flanking the center contact, with the contacts 227 in contact with the fixed contacts 217. The ends of the strips 226 extend downward beyond the contacts at 228 and are disposed in engagement with the pins 210, which, as previously stated, extend between these ends.

In operation, the heater element leads 171 may be connected into the circuit being controlled. In event an overload occurs, the heating of the resistance element 169 heats the bi-metallic element causing it to expand and the flanges 165 to move outward. The movement of the flanges is restrained, however, by the slides 188 and 190 which cannot move until the plunger 199 is moved out of the detents 195—196. The continued expansion of the strip produces greater pressure on the slides, by which time the bi-metallic element has expanded to such an extent that when the slides are released, the bi-metallic elements spring to an open position snapping or quickly moving the slides to the limit of their movement. At the same time, the ends 209 of the levers 206 are quickly swung apart, which movement is transmitted to the end pins 210, and these in turn being in engagement with the ends 228, quickly disengage the contacts 227 and 217. The contacts remain in their open position until the bi-metallic element cools and returns to its normal position depicted in the drawings and wherein the plunger again engages with the detents.

The plunger and detent mechanism also serve another purpose in that it holds the contacts closed and guards against accidental opening of the contact in event of shock or vibration.

It will be appreciated that the switch of my invention may be connected for controlling various types of apparatus in a variety of manners. The thermal overload sub-switch just described is preferably connected so that the heater element is disposed in the load. The contacts which are opened by the operation of the bi-metallic element are normally closed to complete a circuit to the solenoid in such a manner that when the main contacts are closed the solenoid is operated. In event any sustained overload is encountered after a predetermined time, which is determined by the adjustment of the plunger 199, the thermally operated switch is opened which de-energizes the solenoid and causes the main switch to be opened in the manner described.

One circuit which utilizes all of the elements of the mechanism is illustrated in Fig. 48. In this figure there is shown a main source of power which, for instance, might be three phase alternating current 240 which may be connected to three of the fixed contacts 116a to 116c, inclusive, which are connected through the rotor and the movable contacts to the other fixed contacts 120a

to 120c, inclusive. From the first line 120a a circuit is completed to a terminal M1 which may be one of three terminals of a three phase motor, through the heated element 169a. A connection is also made from the load side of this line to the solenoid winding 92.

Terminal 120b, which may be the center or common line, is connected directly to the center terminal M2 of the motor and a lead is also taken off of this wire for the operation of "auxiliary" apparatus.

From the terminal 120c connection is made through the other heater element 169c to the third terminal M3 of the motor.

The other two sets of terminals 116d—120d and 116e—120e may connect directly to the auxiliary apparatus.

The solenoid winding connects to the outer contacts 227 of one of the thermal switches, thence through the center terminal 217 to the outer terminals of the other thermal switch and through its center terminal by the line 241 to the auxiliary apparatus.

It will, therefore, be seen that the thermal switch is responsive to the load in motor circuit, and that when this load is increased to open the thermal switch, the solenoid which is connected in the auxiliary circuit will operate to open the main circuit and also open the auxiliary circuit.

It will, therefore, be seen that I have provided an improved snap action structure which provides a smooth quick action and yet is extremely rugged and compact. The manner in which the rotor rotates between the stationary contact supports with the ribs extending into closely spaced relation to the grooves decreases the tendency for the same to arc and burn the insulating material even though relatively heavy loads are being controlled. The switch will automatically open in event of power failure due to the de-energization of the solenoid and thus adds a safety factor highly desirable in many operations.

The overload release characteristics are also highly desirable, particularly because it is adjustable to cause release after any predetermined time. Thus, overloads of short duration may occur, if desirable, without causing the switch to open.

The thermal switch provides for a snap action which eliminates the tendency of the same to arc.

It will be appreciated that the thermally responsive element, although shown and described as being particularly useful in operating the contacts which control an electrical circuit, is also useful in other devices than that shown and described. For instance, the element could be used to control the operation of valve means. Furthermore, although I have shown a heater element of the resistance type, it is quite within the purview of my invention to heat the bimetallic element by other means; for instance, the heat could be supplied to the interior of the element by a rod of conducting material, or it could be heated by directing a current of fluid through the cylinder. Furthermore, it could be heated by applying radio frequency currents thereto in a manner well known to those versed in the art.

It will also be apparent that although only one pair of detents are shown for the slides which delay the operation of the bimetallic element, with this construction, additional detents can be provided on the slides which engage the elements when in the open position and hold the element against contraction until a predetermined amount of cooling takes place. Furthermore, although

I have shown the bimetallic elements as moving the operating flanges apart upon heating of the element, it is quite within the purview of my invention to provide an element wherein the flanges tend to close together upon heating, by simply forming the element in the opposite directions; that is, with the higher expansible metal on the outside instead of the inside of the cylinder.

10 It will be appreciated that although I have shown only one resistance element for heating the bimetallic element, it is within the scope of my invention to employ more than one resistance element. That is, the bimetallic element could have a resistance element disposed on the outside as well as the inside, or in the structure shown, the bimetallic element could have another resistance element disposed inside of it. These resistance elements could be connected in separate circuits if desired to cause the operation of the switch upon overload in any one of the circuits.

Having thus described my invention, I am aware that numerous and extensive departures may be made therefrom without departing from the spirit or scope of my invention.

I claim:

1. An apparatus for use with a switch of the class described for controlling an electrical circuit having a pair of fixed members carrying fixed contacts and a rotor carrying movable contacts for circuit closing engagement with the fixed contacts, means for communicating a snap action to said rotor movable quickly from a normal position where the contacts are open to a position where the contacts are closed, and operable to quickly move the contacts from the closed to the open position comprising a first lever and a second lever and spring means connecting said levers, latch means for restraining movement of the second lever upon movement of the first lever from either position and means on the first lever to release said latch means upon a predetermined amount of relative movement therebetween, a solenoid connected into and energized by said circuit and means under control of said solenoid for holding said latch means in a state of release from said second lever when no power is flowing in said circuit and for causing said latch means to release said second lever from the closed contact position in event of power failure, and spring means connected to said rotary shaft to rotate said lever to switch open position upon release of said latch.

2. An apparatus for use with a switch mechanism having a plurality of stationary contacts and a rotor carrying movable contacts adapted upon rotation to move said movable contacts into engagement with the fixed contacts for controlling an electrical circuit, means for rotating said rotor quickly from contacts open position to contacts closed position or vice versa comprising rotary shaft, a first lever rigidly carried by said shaft and a second lever rotatably carried by said shaft and operatively connected to said rotor, spring means resiliently connecting said levers to each other, a first latch means for locking said second member against movement in a normal switch open position and means operable by said first lever upon relative movement of the first lever to release said latch means, said spring means adapted to rotate said second lever when released to a switch closed position, and a second latch means for locking said second lever in a switch closed position, said first lever adapted to release said second latch means upon a predetermined

relative movement between the first and second levers, and means including a solenoid disposed in said electrical circuit, adapted to release said second latch means and spring means connected to said rotary shaft to rotate said levers to switch open position upon de-energization of said solenoid including a lever disposed for engagement with said latch means and a plunger on said solenoid and spring means for pressing said plunger against said lever.

3. An apparatus for use with a switch having spaced fixed contacts and a rotor having movable contacts for movement into engagement with fixed contacts to control an electrical circuit including a snap mechanism for rotating said rotor with a quick make and break of said contacts comprising a rotary shaft and a first lever rigidly carried thereby, a second lever rotatably journaled on said shaft and connected to said rotor, means to transmit swinging force from the first lever to the second lever comprising a spring disposed in engagement with said lever for holding them resiliently in a predetermined position relative to each other, latch means for holding said second lever against movement in a normal position wherein the switch contacts are open and in an operated position where the contacts are closed, said first lever adapted to be swung relative to said second lever to increase the tension on said spring means therebetween and adapted upon a predetermined relative movement therebetween to disengage said latch means and said spring means to rotate said second lever to close said contact upon disengagement of said latch means and said latch means adapted to lock said second lever in the contact engaged position, electrically operated means in said circuit operable upon closing said circuit to position said latch means for engagement with said second lever and operable upon failure of power in said circuit to release said latch means, and means connected to said rotary shaft to simultaneously rotate said levers back to a normal position and open said contacts upon release of said latch.

4. A snap action mechanism of the class described including a rotatable shaft, a first lever rigidly disposed on the shaft and swingable thereby, a second lever rotatably journaled on said shaft, spring means engaging said levers operatively connecting the first lever to the second lever, said second lever extending beyond the first lever and formed with a detent therein, locking means for engagement with said second lever including a plunger and spring means for urging said plunger into said detent, said lever being formed with a passage opening into said detent and a movable member disposed in said passage, said first lever being provided with a laterally disposed cam surface adapted upon relative movement between said levers to be swung into engagement with said movable member for moving said member against said plunger to disengage the plunger from said notch and release the second lever.

5. A snap action mechanism of the class described including a rotatable shaft, a first lever rigidly carried by said shaft, a second lever rotatably journaled on said shaft, spring means connecting the first lever to the second lever, said second lever extending beyond the first lever and provided with an arcuate end portion formed with a notch therein, locking means for engagement with said second lever including a plunger and spring means for urging said plunger into said notch, said lever being formed with a pas-

sage opening into said notch and a ball disposed in said passage, said first lever being provided with a pair of laterally disposed cam surfaces adapted upon relative movement between said levers to be alternately swung into engagement with said ball, said ball adapted to be pressed by either one of said cam surfaces against said plunger to disengage the plunger from said notch and permit movement of the second lever to an alternate position, and a second plunger for engagement with said second lever to hold said lever, said cam surface adapted to release said second plunger likewise upon relative movement of the two levers.

15 6. A snap action mechanism adapted to convert a slow swinging movement to quick snap movement including a shaft adapted to be swung, a first lever rigidly carried by said shaft, a second lever rotatably carried by said shaft and having portions journaled on opposite sides of said first lever, a spring and detent carried by said second lever and engageable with the first lever to resist movement of the first lever relative to the second lever, first spring means connected to said levers for holding said levers in alignment with each other and resisting relative movement between the levers, said second lever having a portion disposed beyond and opposite to the end of the first lever, latch means for engagement with the second lever to hold it against swinging movement when the first lever is swung including a plunger disposed opposite the end of the second lever, said second lever being formed with a slot, second spring means engaging said plunger for holding said plunger in said slot, and means carried by the first lever to release said latch upon a predetermined swing of the first lever to permit said first spring means to swing said levers back into alignment comprising an opening formed in the second lever opposite said plunger and a ball disposed in said opening, said first lever being provided with a projection adapted upon a predetermined relative swing of the first lever to engage said ball to push said ball against said plunger out of said slot.

45 7. A snap action mechanism including a first lever, means for swingably supporting said lever, a second lever rotatably carried by said means adapted for movement relative to the first lever, 50 said levers being formed with necked-in seats spaced from the support means and spring means surrounding the supported ends of the lever and seated in said seats to hold said levers resiliently against relative movement to each other, said 55 second lever having portions disposed on opposite sides of the first lever and said first lever being movable between said portions, said portions extending beyond the free end of the first lever and supporting a member opposite to and 60 beyond the end of the first lever, said member being formed with a curved surface provided with a notch extending transversely thereacross in the midportion of said surface and with an opening toward the end of the first lever and 65 through said notch, and ball means disposed in said opening, latch means for engagement with said second lever to hold it against movement in a normal position and a swung position comprising a block disposed beyond the end of said second lever and formed with spaced channels opening toward the axis of the support for said levers, plungers disposed in said channels and 70 spring means for urging said plungers toward said arcuate surface, said plungers adapted for alternate locking engagement with said notch in 75

said second lever, said first lever being provided with laterally extending projections at its end, said projections being formed with surfaces adapted upon relative swinging movement of the first lever to the second lever to engage said ball means and press said ball means downward into said notch to disengage the plunger engaged in said notch, said plungers when out of said notch adapted to ride on said arcuate surface.

8. A snap action mechanism including a first lever, means for swingably supporting said lever, a second lever rotatably carried by said means adapted for movement relative to the first lever, and spring means to hold said levers resiliently against relative movement to each other, said second lever having portions disposed on opposite sides of the first lever and said first lever being movable between said portions, said portions extending beyond the free end of the first lever and supporting a member opposite to and beyond the end of the first lever, said member being formed with a curved surface provided with a notch extending transversely thereacross in the midportion of said surface and with an aperture opening through said notch and toward the end of the first lever and ball means disposed in said aperture, latch means for engagement with said second lever to hold it against movement in a normal position and a swung position comprising a block disposed beyond the end of said second lever and formed with spaced channels opening toward the axis of the support for said levers, plungers disposed in said channels and spring means for urging said plungers toward said arcuate surface, said plungers adapted for alternate locking engagement with said notches in said second lever, said first lever being provided with laterally extending projections at its end, said projections being formed with surfaces adapted upon relative swinging movement of the first lever to the second lever to engage said ball means and press said ball means downward into said notch to disengage the plunger engaged in said notch, said plungers when out of said notch adapted to ride on said arcuate surface and one of said plungers being provided with independent releasing means for releasing said plunger without relative movement between the levers.

9. A snap action mechanism including a first lever, means for swingably supporting said lever, a second lever rotatably carried by said means adapted for movement relative to the first lever, said lever being formed with necked-in seats spaced from the support and spring means surrounding the supported ends of the lever and seated in said seats to hold said levers resiliently against relative movement to each other, said

second lever having portions disposed on opposite sides of the first lever and said first lever being movable between said portions, said portions extending beyond the free end of the first lever and supporting a member opposite to and beyond the end of the first lever, said member being formed with a curved surface provided with a notch extending transversely thereacross in the midportion of said surface and with an aperture opening through said notch and toward the end of the first lever and ball means disposed in said aperture, latch means for engagement with said second lever to hold it against movement in a normal position and a swung position comprising a block disposed beyond the end of said second lever and formed with spaced channels opening toward the axis of the support for said levers, plungers disposed in said channels and spring means for urging said plungers toward said arcuate surface, said plungers adapted for alternate locking engagement with said notches in said second lever, said first lever being provided with laterally extending projections at its end, said projections being formed with surfaces adapted upon relative swinging movement of the first lever to the second lever to engage said ball means and press said ball means downward into said notch to disengage the plunger engaged in said notch, said plungers when out of said notch adapted to ride on said arcuate surface and one of said plungers being provided with independent releasing means for releasing said plunger without independent relative movement between the levers and spring means for simultaneously swinging said levers back to normal position upon release of said plunger.
